DEVICE FOR APPLYING SHEET MATERIAL
TO CYLINDRICAL ARTICLES

Francis C. Worth, Brooklyn, N. Y.

Application May 31, 1949, Serial No. 96,367

18 Claims. (Cl. 216—45)

1

This invention relates to devices for applying labels to various types of objects such as ampules, receptacles of various descriptions, or any type of article which has at least a portion of the outer surface thereof of substantially cylindrical shape.

An object of this invention is to apply a label from the bottom of a padded stack of labels on an article by discharging one of a group of articles on a plurality of rails, the rails being fixed for movement with the carriage; operate the carriage in a part of a reciprocatory cycle of operation so that the ampule or other article is deposited in a nest, the nest having a roller forming the bottom thereof; pivotally operate a receptacle which has a cementitious product or adhesive material therein so that an improved applicator contacts the bottom label of the padded stack of labels applying in substantially parallel lines a proper quantity of the adhesive; then while the roller is imparting rotative movement to the article and while the nest is translating the article together with the movement of the carriage, raise the roller, thereby lifting the article while it is continuing to rotate so that the article contacts the front or leading edge of the bottom label which has adhesive material thereon whereby the label sticks to the article during the rotation and translation thereof so that the label is peeled from the stack; then move the article further with the carriage, and more specifically in the nest, while this last movement takes place, press the article firmly against the roller so that the label is pressed tightly thereon, and finally lower the roller to form a discharge opening for the now-labeled article.

After the roller has been lowered in order to discharge the article, the receptacle having the applicator carried thereby is displaced in a pivotal manner, lowering it preparatory to the next similar cycle of operation.

A further object of this invention is to teach a new and useful method of applying labels to small articles (preferably), such as ampules, and to teach the construction of a relatively simple (relative to conventional apparatus) structure to serve the same purpose, the method embodying a novel sequence of steps while the apparatus embodies a novel combination of elements.

To the best of my knowledge, the only machine used in the trade for performing a function somewhat similar to the main object of my invention weighs approximately two tons and uses various screws, jacks and the like for feeding labels.

2

This machine does not completely apply the label to the ampule but only partially applies the same, it requiring human contact on the ampule and label to complete the operation. Hence, it is another object of my invention to completely apply a label to a small article having at least a portion of the outer surface cylindrical without the necessity of touching either the article or the label except for filling the hopper with articles and filling the magazine with labels.

Another object of this invention is to utilize padded labels, that is, labels which are joined in a pad and rely on the adhesive material applied to the bottom label of the stack for holding one end of the lowermost label on the article and due to the rotation and translation of the article, tear or peel the bottom label from the stack while it is being firmly fixed to the article.

Ancillary objects and features of novelty will become apparent in following the description of the preferred form of the invention, illustrated in the accompanying drawings and described as my method or process.

In the drawings:

25 Figure 1 is an elevational side view of the illustrated form of the device;

Figure 2 is a plan view of the device shown in Figure 1;

Figure 3 is a longitudinal sectional view taken substantially on the line 3—3 of Figure 4 and in the direction of the arrows;

Figure 4 is a vertical sectional view taken on the line 4—4 of Figure 1 and in the direction of the arrows;

35 Figure 5 is a longitudinal sectional view taken on the line 5—5 of Figure 2 and in the direction of the arrows;

Figure 6 is an enlarged sectional view showing the carriage positioned on the frame different from that of Figure 1 and exemplifying relative positions of elements in a part of the cycle of operation of the carriage;

45 Figure 7 is a schematic illustration of one phase of operation of the device showing both the discharge of an article to be labeled and the discharge of several other articles which have been labeled;

Figure 8 is a schematic view of a portion of the device illustrative, particularly, of the position of various parts when an article is being deposited in the nest formed in the carriage;

50 Figure 9 is a schematic elevational view showing the various positions of parts of the device immediately after the bottom label of the stack 55 has been removed and is being pressed on the ar-

ticle by resiliently urging the article against the roller which forms the bottom of the nest;

Figure 10 is a transverse sectional view of the structure involved in the schematic illustration of Figure 8 and taken on the line 10—10 thereof;

Figure 11 is a sectional view taken on the line 11—11 of Figure 10 and in the direction of the arrows;

Figure 12 is a sectional view showing a typical arrangement of supporting one of the very small articles, in this instance an ampule, the view having been taken substantially on the line 12—12 of Figure 5 and in the direction of the arrows;

Figure 13 is a wiring diagram of the electrically operative units used in connection with the device; and

Figure 14 is a partial schematic and partial sectional view illustrative of how the bottom label of the padded stack is taken and wrapped around the article as the article is being simultaneously translated with respect to linear movement and rotated within the nest.

Used today for applying labels to ampules is a machine which partly applies the label to the ampule. Thereafter, it is essential that the label be pressed manually around the very small article and straightened during this operation. A person capable of completing the label application on the ampule at the rate of fourteen per minute is considered highly skilled. The present device performs the complete operation on each ampule, obviating the necessity of contacting either the label or the ampule by hand. The completion of from forty to sixty label applications on ampules has been successfully performed in use of the present machine.

After manually placing the label on the ampule, it is necessary to inspect the label to see that it is applied on the ampule straight and even. By utility of the device illustrated in the drawings, it has been found possible to apply a label on an ampule in a perfectly straight and even manner. Hence, inspection of labeled ampules is practically entirely obviated. A frame, generally indicated at 10, is provided of any suitable material and is made sufficiently large to accommodate the necessary elements to be described subsequently. The device, in general, is extremely small, since its prime utility is in connection with small articles which are difficult to handle. A cover (unshown) is disposed around the frame 10 for enhancing the appearance of the apparatus. However, to show the working elements involved, the cover is removed in the drawings.

The frame or framing 10 includes only sufficient structural members to accommodate the various electrical and mechanical elements. A cross member 12 forms a part of the frame as well as the plurality of legs. Disposed on the cross member 12 is a motor 14 which has a transmission 16 operatively connected therewith. A pulley 18 is fixed in any suitable manner to the power shaft 20 of the transmission and has a belt 22 entrained therearound. This belt also extends around a driving wheel 24 which is mounted on a stub shaft 26. The stub shaft 26 is in turn supported by brackets 28 and 29 which depend from upper side members or sides 30 and 32, respectively, of the frame 10.

A gear 34 having the engineeringly proper and appropriate number of teeth is fixed to the shaft 26 and has a conventional driving chain 36 extending therearound. Suitable thrust bearings 38 and 40, respectively, are used for the purpose of

maintaining the shaft 26 in the proper centered position with respect to the brackets 28 and 29.

The chain 36 extends around a gear 42 after passing through a guide 44 which is fixed to the upper side of the frame 10.

A star wheel 46 is secured to the shaft 48 which is passed through the back end of a hopper 50. Hence, operation of the motor is imparted through the driving wheel 24 in rotative movement to the star wheel 46. Since the star wheel is disposed in the hopper 50 adapted to maintain a supply of articles, operation of the star wheel will deposit, successively, single articles into the guide 52 which is fixed at the discharge end of the hopper.

Noting Figure 4, it is seen that the hopper 50 is tilted with respect to the vertical so that the articles will, by the force of gravity, be retained at the back part of the hopper. A baffle 56, fixed in the hopper, directs the articles, which are ampules, in this instance, into the star wheel for subsequent disposition into the guide 52.

A substantially vertical bracket 58 is fixed to the upper side of the frame 32 by means of screws or suitable equivalent members such as rivets, welding, etc., and has bolts 60 passed therethrough and also through parts of the hopper to retain it in the proper position on the frame.

A pitman 62 is secured at one end in eccentric relationship with respect to the driving wheel 24 and fixed at the other end to a driving arm 64. The function of the driving arm 64 is to operate a carriage which is disposed on the upper part of the frame, in a reciprocatory travel, so that it is capable of performing successive reciprocatory cycles of operation. The carriage (Figure 4) consists of a pair of sides 68 and 70, respectively, which are held in substantially parallel spaced relation by means of a plurality of spacers 72. Longitudinal channels 74 and 76 are formed in the inside surfaces of the sides 30 and 32 of the frame. These channels may be milled in the sides 30 and 32 or may be formed by placing strips 78 and 80 in suitable channels in the sides, utilizing a shoulder as the other confining wall of each channel. Rollers 80 disposed on axles 82 are mounted for movement in the channels 74 and 76. Since the axles pass through the sides 68 and 70 of the carriage and sleeves 84 are disposed around the axles, the roller axle assemblies serve also in the nature of spacers for the sides 68 and 70 of the carriage. As disclosed in Figure 3, the driving arm 64 is fixed to the side 68 of the carriage, whereby, upon operation of the pitman 62, the carriage is reciprocated.

A substantially channel-shaped magazine having an open front, top and bottom is fixed to the side 32 of the frame 10 by means of the vertical bracket 58 and through the medium of an adjusting assembly. The channel 88 is adapted to support for gravity feed a stack of padded labels 90. To maintain the channel in adjusted position so that proper discharge from the magazine may be obtained, a pair of similar assemblies are used. Each assembly includes a screw 92 which has its head countersunk in the web part of the channel and passes through a part of the vertical bracket 58. Adjusting and locking nuts 94 and 96, respectively, are disposed on the threaded part of the screw 92 and a third nut 98 is disposed adjacent the back part of the magazine channel member. A spring 100 is interposed between the back surface of the channel member 88 and the nut 98. Flanking set screws 102 and 104, respectively, are passed through the substantially vertical bracket 58 and engage the

outside back surface of the channel 88, whereby rotative adjustment of the channel about a vertical axis may be obtained. This adjustment is desirable in that the angle of application of the label from the padded stack 90 can be regulated by rotation of the channel about a vertical axis.

In Figure 12, the shape of the particular article being labeled is evident. This is an ampule 106 having a portion of the exterior surface thereof cylindrical. After the ampule 106 is deposited into the guide 52 from the star wheel 46, it falls on two of a plurality of rails 108, 110 and 112. To make certain that the ampule falls properly on the rails 108 and 112, a resilient clip 114 is disposed on a part of the side wall of the guide. These rails are fixed to the carriage between the sides 68 and 70 by means of suitable screws 118.

To accommodate the peculiar top portion (in shape) of the ampule 106, the rail 112 is fairly sharp at the top thereof, while the rail 108 which accommodates the rear part of the ampule is flat on the top surface. The rail 110 has a relatively sharp top surface and is slightly lower than the rails 112 and 108. The rail 110 serves an entirely different purpose from the rails 108 and 112 and will be described subsequently.

A transverse baffle 120 extends between the sides 68 and 70 of the carriage and has a stop 122 fixed thereto, extending rearwardly toward the rails. The distance between the stop 122 and the nearest ends of the rails 108, 110 and 112 forms a nest for disposition of the ampule 106 (Figure 6).

The forward end of the rail 112 is curved downwardly, while the forward end of the rail 110 extends further a slight amount but has a decided taper 124 at the lower front edge thereof. A receptacle 128 is mounted at one end for displacement, specifically, pivotal movement about a pin 130, and is supported at the other end on an eccentric 132. A shaft 134 supports the eccentric so that it will rotate beneath the receptacle 128 and contact the wear plate 136. This wear plate is fixed to the under surface of the receptacle 128. In order to enhance the frictional bond which is used for retaining the receptacle in the various positions, a spring 140 is disposed in concentric relationship with the pivot pin 130, engaging the outside surface of the receptacle and the side 70 of the carriage. A shim or thrust bearing 142 is disposed on the pivot pin 130 on the opposite side of the receptacle 128 from the spring 140 and is used for properly centering the receptacle.

A heater 144 is fixed to the bottom surface of the receptacle 128 and has a pair of lead wires 146 and 148 operatively connected therewith through suitable contacts. The leads 146 and 148 connect with a switch 150 which is suitably mounted on the framing of the device and there is a rheostat 152 interposed in one of the lines.

What is known as a "hot melt" or, alternatively, a heat softenable adhesive, is used as the adhesive material or cementitious product for application to the bottom label of the stack of labels. Hence, it is necessary to heat the receptacle 128 and maintain it in the heated condition. Since the receptacle is fixed to the carriage and the carriage reciprocates, the contacts (Figure 1) 160 and 162, respectively, which extend from a suitable insulating block 174, fixed to the framing, are used. Brushes 166 and 168 are secured to the arm 64 for movement with the carriages and they slide on the contacts 162 and 164 in order to maintain the circuit of the heater 144 complete at all times. A stop 170, which is in-

sulating in nature, is fixed at the ends of the contacts 162 and 164 in order to maintain 166 and 168 equidistant.

Means for applying a quantity of adhesive from the receptacle 128 to the lowermost label of the stack 90 is provided. This means consists of a pair of shafts 174 and 176, respectively, each of which has rollers 178 and 180, respectively, disposed thereon. The roller 178 is disposed within the receptacle as deep as practically possible and is partially submerged in the adhesive. The roller 180 has a number of disks 182 thereon which are very close to the roller 178 so that the heated adhesive may be transferred from the roller 178 to the disks 182. Passed between a pair of the disks is an arm 184 which is fixed at one end by a bracket 186 and fixed at the other end to the baffle 120. There is a notch supplied in the arm 184 so that it will not interfere with the operation of the roller 180 and the function of the arm is to support the stack of labels during one part only of one stroke of the reciprocatory cycle of operation of the carriage.

Gears 190 and 192, respectively, are fixed to the shafts 174 and 176. These gears are also enmeshed so that operation of one, of necessity, imparts rotation to the other.

The gears are operated during a portion only of one stroke of the reciprocatory cycle of operation of the carriage. This is occasioned through the use of the rack 194 which is supported by a bracket 196 (Figure 1). Suitable screws or the like maintain the bracket 196 on the side 30 of the frame.

The roller 198 which is mounted on the shaft 200 preferably is made of resilient material or has a resilient cover. The shaft 200 has wheels 202 at the ends thereof which are disposed on the upper edges 204 and 204' of members 30 and 32 serving as rails and also cams. There are two rollers 202 provided and two rails 204 and 204'. These rails are the upper edges of the sides 30 and 32 of the frame 10 while there is one roller provided on each end of the shaft 200. According to the shape of the rails, both of which are substantially alike, the behavior of the roller 198 will be influenced during the reciprocatory movement of the carriage. Accordingly, since the roller 198 forms the bottom of the nest, the ampule 106 which is disposed in the nest is directly affected and motivated by movement of the roller.

Fixed to the bracket 210 which is secured to the side 30 of the frame is an assembly for resiliently pressing the ampule and all subsequent ampules against the roller 198. This resiliently operated means includes a pair of flat members 212 and 214, respectively, which have their ends disposed in notches in the bracket 210 and bracket 216, also supported by the side of the frame 10. The ends of the flat members 212 and 214 are also notched, as at 218 and 220, to allow a predetermined amount of vertical movement thereof. Screws 222 and 224, respectively, pass through upper plates 226 and 228 which rest on parts of the flat members or plates 214 and 212, and the screws are fastened in threaded openings in the brackets 210 and 216. Since springs 230 and 232, respectively, are disposed between the heads of the screws 222 and 224 and the plates 226 and 228, respectively, the substantially flat members 212 and 214 are constantly urged downwardly. Accordingly, when an ampule is moved under the members 214 and 212, the said members are pressed against the springs 230 and 232,

thereby forcing the ampule against the roller 198 on which it is disposed.

It is absolutely necessary that only the proper amount of adhesive be applied to the bottom label of the stack 90. For this reason the doctor knife 234 which has an inturned end portion 236 is employed. The doctor knife 234 is of resilient material and has a bow 236 therein. A yoke 238 is fixed to the bottom of the receptacle 128 and has a set screw 240 disposed therein with an end contacting the bow 236. Since one end of the doctor knife is fixed to the receptacle and the setscrew engages the bow 236, adjustment of the set screw will be reflected in various positioning of the inturned end 236 of the knife. This spaces it farther or closer to the pickup roller 178.

The stack of labels is padded, as disclosed in Figure 6. That is, there is an amount of a binder 244 along opposite edges of all of the labels holding them together. This binder begins about forty per cent of the distance from the leading edge of the labels and terminates about ten per cent of the entire distance) from the trailing edge of the labels. This is of importance in that since the adhesive material clinging to the ampule 106 is used for the purpose of peeling or tearing the bottom label from the stack 190, the spacing of the binder 244 from the front end allows an appreciable amount of the lower label to come into firm fixation with the substantially cylindrical part of the surface of the ampule 106.

Reference to Figure 14 discloses that in practical use more than one of the bottom number of labels will tend to pull loose from the stack. However, due to the rail 110 being lower and beveled down at the front end all but the bottom label is prevented from being pulled from the padded group of labels.

The labels in this apparatus are gravity-fed. The small, substantially U-shaped slide 250 has its ends curved around the channel 88 which forms a part of the magazine in order to hold a weight 252 which is disposed therein. This weight rests on the top label of the stack 90, constantly pressing the entire stack downwardly for discharge. In order to hold the lowermost labels in proper position, a guide 254 having fingers 256 and 258 is disposed adjacent the lower open end of the channel 88, preventing non-vertical removal of the lower label of the stack 90.

Operation

Referring primarily to the three diagrammatic showings (Figures 7-9), the operation of the invention is most readily understandable. Due to the motor-operated chain and gearing, the star wheel 46 first deposits an ampule 106 into the guide 52. This ampule is at rest as disclosed in Figure 12 on the outside and inside rails 108 and 112 respectively. At this time, the roller 198 is in the "down" position, since the wheels 202 are disposed in the depression 260 of the rails 204. The shaft 200 being guided in the slightly curved slots 262 formed in the sides 68 and 70 of the carriage makes it possible for the shaft 200, and consequently the roller 198, to assume a slightly arcuate path of travel. This forms an opening between the baffle 120 and the roller 198 for discharge of ampules, whereby they are conducted through the spout 264 for deposit on a conveyor belt or any other desired location.

The carriage moves to the left from the position in Figure 7 due to the operation of the pitman rod 62 as influenced by the driving wheel

24. Accordingly, the wheels 202 ride upwardly out of the depressions 260. Meantime, the nest approaches the ampule 106. Moving the carriage slightly further allows the ampule 106 (Figure 8) to be deposited from the guide 52 into the nest and on the roller 198. Meanwhile, the arm 270 which is fixed to the shaft 134 having the cam 132 thereon strikes the stop 272 which is fixed to the inside surface of the side 32 of the frame. 5 By striking the stop in this portion of the whole cycle of reciprocatory operation of the carriage, the shaft 134 is rotated, carrying the cam 132 with it and pivotally operating the receptacle 128 about the pin 130 as an axis or pivot point. This 10 raises the gears 190 and 192 so that the gear 190 becomes enmeshed with the rack 194.

In completing the single cycle of operation, the carriage is moved toward the right as disclosed in Figure 9, with the cams retained in the rotated 20 position due to the spring 280 which reacts on one of the cams 132 (two provided on the shaft 134) and also on the side 10 of the carriage. The small gear train being enmeshed with the rack imparts rotative movement to the adhesive material applicator rolls or rollers so that the knives 182 apply adhesive material to the bottom layer 25 of the label of the stack in longitudinal lines which are substantially parallel to each other.

Moving the carriage further to the right, the 30 ampule 106 (Figure 14) which is disposed in the nest and on the roller 198 engages the now adhesive front portion of the lower surface of the bottom label of the stack of labels 90, causing it to stick thereto. Rotation is imparted to the 35 ampule 106, since the roller 198 is rotating because of the wheel engagement with the cam and the ampule is also being translated due to the movement of the carriage having the nest formed thereon. The linear speed of the ampule, insofar as 40 translation is concerned, and the linear speed of the ampule, insofar as rotative movement is concerned, are the same so that the label will be applied and held on the ampule without it pulling. The operation of removal of the bottom 45 label from the stack 90 is peeling.

However, if the ampule 106 were to remain at the same elevation throughout the whole cycle of operation, it could not contact the bottom label of the stack. Accordingly, the depression 285 50 in the cam track allows the roller to fall slightly prior to reception of the ampule 106 on the roller 198. But, just prior to the engagement of the ampule with the lowest label of the stack, the shape of the cams 204 and 204' are such as to 55 cause roller 198 to raise, thereby raising the bottom of the nest so that the ampule engages the bottom label of the stack 190.

In moving the carriage further, the stop 288 which is carried by the side 32 of the frame is 60 engaged by the arm 270 thereby rotating the cam 232 and permitting the receptacle 228 to be displaced in a pivotal manner to the "down" position. Also, the wheels 202 are disposed in the depression 260, thereby causing the bottom of the nest to fall and form a discharge opening for the now-labeled ampule.

It has been found that the best type of adhesive material is a hot melt, and accordingly this 70 type of adhesive material is suggested for use in the receptacle 128. This necessitates the operation of the switch 158 some time prior to the actual operation of the carriage. Hence, the switch 290 is wired into the leads 291 and 292. This switch controls the motor 14 independent of 75 the operation of the heater 144.

After the contents of the receptacle 128 have been heated sufficiently so that the device may be operated properly, adjustment of the rheostat 152 renders it possible to maintain the proper temperature in the receptacle 128.

Since the padded stack of labels 90 is of the gravity-feed type, provision must be made for retaining them in such disposition with respect to the remainder of the apparatus as to allow one (the bottom) label to be peeled from the stack, yet retain the entire stack in the proper position within the magazine. Accordingly, the center rail 110 is used for the purpose of supporting the stack during the discharge of the ampule 106 on the rails 112 and 108 and until shortly before the ampule 106 is disposed in the nest. When the ampule 106 is actually being disposed in the nest, the applicator roller has its disks 182 disposed below the upper surface of the arm 184. Hence, it is the arm 184 which contacts the bottom label of the stack 90 while the ampule 106 is being disposed on the roller 198. After disposition of the ampule or at about the same time as the disposition of the ampule on the roller 198, the arm 270 engages the stop 272, thereby urging the receptacle 128 about the pivot pin 130 and forcing the knives or disks 182 in side by side relationship to the arm 184. Hence, at this particular time the weighted stack of labels 90 is being pressed by means of the weight 252 on the knives of the applicator 182. Thereafter, the stack of labels is supported by means of having its bottom one engage the ampule 106. Prior to complete removal of the bottom label from the stack 90, the center rail 110 becomes again disposed beneath the new bottom label of the stack 90.

As described, the removal of the bottom label is effected in such a manner that the bottom label is peeled from the group, as distinguished from being pulled or pressed thereagainst by some mechanical means other than the actual weight of the gravity-fed stack of labels. Since the roller 198 is held in the "up" position between the depressions 285 and 269, the force of the springs 239 and 232 is used to press the members 212 and 214 against the ampule, urging it firmly against the preferably rubber-covered roller 198. Thereafter, upon dropping of the roller 198 into the lowered position, the particular ampule 106 under discussion is permitted to pass through the discharge opening between the stop 122 which reacts in connection with the ampule 106, and the roller 198. A small part of the edge 283 of the stop 122 is cut away (Figure 14) in order to allow free falling of the ampule 106 through the funnel 264.

Having described the invention, what is claimed as new is:

1. A device for fixing labels to substantially cylindrical surfaces of articles comprising a frame and a carriage disposed on said frame, means operatively connected with said carriage for horizontally reciprocating said carriage, an article supporting nest provided in said carriage, a roller carried by said carriage forming the bottom of said nest to accommodate an article, a label magazine carried by said frame and disposed above the nest in the carriage, means secured to said carriage for applying a cementitious product to the bottom label in the magazine while the carriage is being moved, the bottom label being in the path of travel of the cylindrical surface so that the bottom label together with

the cementitious product thereon is applied on the cylindrical surface.

2. A device for fixing labels to substantially cylindrical surfaces of articles comprising a frame and a carriage disposed on said frame, means operatively connected with said carriage for horizontally reciprocating said carriage, an article supporting nest provided in said carriage, a roller carried by said carriage forming the bottom of said nest to accommodate an article, a label magazine carried by said frame and disposed above the nest in the carriage, means secured to said carriage for applying a cementitious product to the bottom label in the magazine while the carriage is being moved, the bottom label being in the path of travel of the cylindrical surface so that the bottom label together with the cementitious product thereon is applied on the cylindrical surface, a cam on said frame, and means connected to said roller and located on said cam to raise and lower said roller in response to the shape of the cam, said cam being so shaped as to raise the means connected to the roller and thereby raise the roller forming the bottom of the nest after an article has been deposited thereon and when the article has approached the bottom label thereby assuring firm engagement of the label and surface.
3. A device for fixing labels to substantially cylindrical surfaces of articles comprising a frame and a carriage disposed on said frame, means operatively connected with said carriage for horizontally reciprocating said carriage, an article supporting nest provided in said carriage, a roller carried by said carriage forming the bottom of said nest to accommodate an article, a label magazine carried by said frame and disposed above the nest in the carriage, means secured to said carriage for applying a cementitious product to the bottom label in the magazine while the carriage is being moved, the bottom label being in the path of travel of the cylindrical surface so that the bottom label together with the cementitious product thereon is applied on the cylindrical surface, a cam on said frame, a shaft forming a part of said roller, a wheel carried by said shaft and disposed on said cam, said cam being so shaped as to raise said wheel, thereby raising the roller forming the bottom of the nest after an article has been deposited thereon and when the article has approached the bottom label thereby assuring firm engagement of the label and surface, and resilient means carried by said frame and disposed over said nest during a part of the path of movement of said carriage for pressing the article against said roller causing the article to rotate on said roller.

4. The combination of claim 2 and said cam having a depression therein accommodating said means which is connected to said roller so that said roller is lowered for discharge of the article disposed thereon.

5. In a labeling apparatus, a frame having a carriage disposed thereon and means for horizontally reciprocating said carriage, a nest formed in said carriage for supporting an article to be labeled, a magazine disposed above said carriage and in the path of travel of the article in the nest, said magazine being adapted to support a gravity-fed stack of labels therein with the bottom label contacting the article as it passes thereunder.

6. In a labeling apparatus, a frame having a carriage disposed thereon and means for hori-

11

zontally reciprocating said carriage, a nest formed in said carriage for supporting an article to be labeled, a magazine disposed above said carriage and in the path of travel of the article in the nest, said magazine being adapted to support a gravity-fed stack of labels therein with the bottom label contacting the article as it passes thereunder, means carried by said carriage for applying an adhesive material to the bottom label prior to the article's contacting the bottom label, and a roller forming the bottom of said nest to facilitate rotative movement of the article in the nest when the carriage is moving.

7. In a labeling apparatus, a frame having a carriage disposed thereon and means for horizontally reciprocating said carriage, a nest formed in said carriage for supporting an article to be labeled, a magazine disposed above said carriage and in the path of travel of the article in the nest, said magazine being adapted to support a gravity-fed stack of labels therein with the bottom label contacting the article as it passes thereunder, means carried by said carriage for applying an adhesive material to the bottom label prior to the article's contacting the bottom label, and a roller forming the bottom of said nest to rollingly support the article in the nest when the carriage is moving, means secured to said frame for raising said roller when the roller approaches a position below said magazine so that the article is pressed against the bottom label of the gravity-fed stack of labels.

8. A machine for applying labels to articles comprising a frame having a horizontally reciprocating carriage carried thereby, an article-retaining nest in said carriage, a magazine disposed over said carriage and adapted to support a gravity-fed stack of labels therein, the labels of which are releasably joined along a part of opposite edges thereof, means forming a part of said nest for raising the article in the nest so that the article is pressed against the bottom label of the stack and so that the rotative movement of the article detaches the bottom label from the stack.

9. A machine for applying labels to articles comprising a frame having a horizontally reciprocating carriage carried thereby, an article-retaining nest in said carriage, a magazine disposed over said carriage and adapted to support a gravity-fed stack of labels therein, the labels of which are releasably joined along a part of edges thereof, means forming a part of said nest for rotating and raising the article in the nest so that the article is pressed against the bottom label of the stack and so that the rotative movement of the article detaches the bottom label from the stack, and means responsive to movement of the carriage for applying an adhesive material to the bottom label of the stack prior to contact of the article with the label caused by the means which forms part of the nest.

10. The process of applying a label from the bottom of a padded stack of labels on an article including the steps of: applying an adhesive material on a part of the bottom label in lines; rotating the article and translating it in a direction substantially parallel to the lines of adhesive material so that the article contacts an end portion of the label; the surface speed of the article and the speed of the translation of the article being substantially equal so that the bottom label is peeled from the pad.

11. A labeler for at least part cylindrical arti-

12

cles comprising a frame, a carriage, means mounting said carriage on said frame for reciprocation, means for actuating said carriage through reciprocatory cycles of operation, a plurality of rails secured to said carriage, two of said rails adapted to support the article, a nest in said carriage at the ends of said rails, a dispenser disposed above said rails to deposit the article on the two rails, the article being deposited in the nest when the carriage has moved a part of the cycle, a magazine for a gravity fed stack of labels, one of said rails supporting the stack, means displaceably carried by said carriage for applying an adhesive material to the bottom label of the stack, means carried by said frame and said carriage and operative at a certain position of travel of the carriage for displacing said adhesive applying means to such position that a part thereof contacts the bottom label of the stack, and a roller forming the bottom of said nest and operable to support the article beneath said magazine so that the article thereon rollingly contacts the bottom label.

12. A labeler for at least part cylindrical articles comprising a frame, a carriage, means mounting said carriage on said frame for reciprocation, means for actuating said carriage through reciprocatory cycles of operation, a plurality of rails secured to said carriage, two of said rails adapted to support the article, a nest in said carriage at the ends of said rails, a dispenser disposed above said rails to deposit the article on the two rails, the article being deposited in the nest when the carriage has moved a part of the cycle, a magazine for a gravity fed stack of labels, one of said rails supporting the stack, means displaceably carried by said carriage for applying an adhesive material to the bottom label of the stack, means carried by said frame and said carriage and operative at a certain position of travel of the carriage for displacing said adhesive applying means to such position that a part thereof contacts the bottom label of the stack, a roller forming the bottom of said nest and operable to support the article beneath said magazine so that the article thereon rollingly contacts the bottom label, means carried by said frame for pressing the label on the article as the nest is moved with the carriage, and means for lowering said roller after passing said pressing means to form a discharge opening for the article.

13. The combination of claim 12 and said adhesive applying means including a heated receptacle pivoted to said carriage, and an applicator roller carried by said receptacle; and an armed fixed for movement with said carriage for supporting the stack of labels during the part of the cycle of operation of the carriage prior to the application of adhesive to the bottom label of the stack.

14. In a labeling machine, a magazine to support a padded stack of labels, a frame supporting said magazine, a carriage disposed on said frame and horizontally movable beneath said magazine, means mounting said carriage on said frame for reciprocation, a nest in said carriage for supporting an article, means carried by said frame for applying an adhesive material to the bottom label of the stack, and means disposed on said carriage for supporting the article for rotation as the nest passes under the bottom label and for displacing the article so that it contacts the adhesive on the bottom label to fix a part of the label on the article and pull it from the padded stack.

15. In a labeling machine, a magazine to support a padded stack of labels, a frame supporting said magazine, a carriage disposed on said frame and horizontally movable beneath said magazine, means mounting said carriage for reciprocation, a nest in said carriage for supporting an article, means carried by said frame for applying an adhesive material to the bottom label of the stack, means disposed on said carriage for supporting the article for rotation as the nest passes under the bottom label and for displacing the article so that it contacts the adhesive on the bottom label to fix a part of the label on the article and pull it from the padded stack, and means carried by said carriage and said frame for actuating said adhesive applying means during only a part of the cycle of operation of the carriage.

16. In a labeling machine, a frame which includes a pair of spaced rails, a carriage, means for mounting said carriage on said frame for reciprocative movement, means forming an article retaining nest in said carriage to carry the article from one end of said frame to the other end thereof with said carriage, a magazine carried by said frame to support a stack of labels above the nest in the carriage, said means forming a nest including a roller, said rails having parts thereof serving as cams, cam and rail engaging means connected to said roller and disposed on the rails and on the cams as said carriage is reciprocated, and said cams being located below said magazine and arranged to raise said roller when the nest is below said magazine so that the article in said nest is lifted to engage the bottom label in said magazine.

17. A labeling machine comprising the combination of a frame, a carriage, means mounting said carriage for reciprocation in a definite plane, means including a roller forming an article supporting nest in said carriage, said roller having end members and said carriage having slots with said end members disposed therein, cams serving as rails and arranged on said frame, said end members being disposed on said cams so that said roller is raised and lowered by said cams when

5 said carriage is reciprocated, a magazine to support a padded stack of labels carried by said frame and disposed above said carriage, means carried by said carriage for applying an adhesive material to the bottom surface of the bottom label of the stack during a part of a reciprocatory cycle of operation of the carriage so that during another portion of said cycle the article which is lifted by the roller engages the bottom label 10 with the adhesive thereon.

15 18. A labeling machine comprising the combination of a frame, a carriage, means mounting said carriage for reciprocation in a definite plane, means including a roller forming an article supporting nest in said carriage, said roller having end members and said carriage having slots with said end members disposed therein, cams serving as rails and arranged on said frame, said end members being disposed on said cams so that said 20 roller is raised and lowered by said cams when said carriage is reciprocated, a magazine to support a padded stack of labels carried by said frame and disposed above said carriage, means carried by said carriage for applying an adhesive material to the bottom surface of the bottom label of the stack during a part of a reciprocatory cycle of operation of the carriage so that during another portion of said cycle the article which is lifted by the roller engages the bottom label 25 with the adhesive thereon, and a presser arranged above said carriage to press the label on the article firmly as the article is translated with the carriage after the label is applied to the article.
